(57) **CLAIM**

The ornamental design for a wheelchair lift, as shown and described.

DESCRIPTION

FIG. 1 is a perspective view of an embodiment of the new design of a wheelchair lift.

FIG. 2 is a front view of an embodiment of the new design of a wheelchair lift.

FIG. 3 is a rear view of the embodiment of the new design of a wheelchair lift.

FIG. 4 is a left side view of an embodiment of the new design of a wheelchair lift.

FIG. 5 is a right side view of an embodiment of the new design of a wheelchair lift.

FIG. 6 is a top view of an embodiment of the new design of a wheelchair lift.

FIG. 7 is a bottom view of an embodiment of the new design of a wheelchair lift; and,

FIG. 8 is a perspective view of an embodiment of the new design of a wheelchair lift in a deployed position.

The subject matter in this patent includes movable components that effectuate a transition exemplarily shown between FIGS. 1 and 8. No ornamental aspects are associated with the process or period of such transition.

The broken line showing of portions or regions, and other elements in the Figures are for the purpose of illustrating unclaimed portions and form no part of the claimed design.

1 Claim, 8 Drawing Sheets
